CALK ASSEMBLAGE FOR SHOES

Clare R. Daniels, Milwaukee, Wis.

Application September 15, 1947, Serial No. 774,105

4 Claims. (Cl. 36—59)

1

The present invention relates generally to improvements in calk assemblages for the soles of athletic or other shoes, and relates more particularly to improvements in the construction and operation of supports and sole mountings for detachable calks or the like.

A primary object of this invention is to provide an improved detachable calk and sole support and mounting therefor which is extremely simple in construction, flexible in its adaptations, and highly efficient in actual use.

Many types of athletic shoes and other shoes for diverse purposes are provided with sole calks, cleats, spikes, or the like adapted to prevent foot slippage; and in most instances, these calks have been relatively standardized and are made removable or detachable to enable ready replacement when desired. As an example, the presently popular and more or less standard golf shoe calk comprises a metal conical spike formed integral with one side of a relatively wide base flange having an integral threaded projection extending centrally away from its opposite side and adapted to coact with an internally threaded bushing firmly secured to the sole of the shoe. The base flanges of these prior calks are usually of circular shape, and are each provided with diametrically opposite socket openings or the like disposed on opposite sides of the protruding spike and adapted to coact with similarly spaced pins of a spanner wrench which is operable to apply and/or remove the calk; but since the span or spacing of the socket openings of the calks produced by different manufacturers varies somewhat, it has heretofore been found necessary to utilize special spanner wrenches for the different types of calks. One of the heretofore most popular and widely used means for securing the calk to the shoe consists of an anchoring member formed with an internally threaded bushing or sleeve adapted for reception of the threaded calk shank and piercing the shoe sole, the bushing being provided with an integral laterally projecting head or flange on the inner end thereof, and means such as spurs projecting from the head or flange in the same direction as the bushing and adapted to be driven into the sole to secure the anchoring member against rotation during application or removal of the calk. Aside from these spurs, or other means such as rivets, associated with the inner head or flange of the bushing or calk receiving nut, no other means is provided in the prior assemblages for securing the anchoring member to the shoe sole or for supporting the calk. Thus, when the calk is

2

screwed tightly into the bushing or receiving nut, the base flange of the calk compresses the adjacent portion of the relatively flexible and soft composition shoe sole in a relatively limited area; and during application of pressure on the spike, as by walking, the sole flexes and causes the cleat assemblage to press inwardly to a considerable extent in a relatively small area against the wearer's foot, thereby creating an uncomfortable feeling. Also because of the flexibility of the sole and the comparatively small area to which the calk is secured, these prior calks and the anchoring means therefor have a tendency to tilt and loosen in the sole with wear.

15 It is therefore a more specific object of my present invention to provide an improved calk assemblage which obviates and/or minimizes all of the above-mentioned disadvantages and objections encountered with the prior art assemblages.

20 Another specific object of the present invention is to provide an improved calk assemblage which may be quickly and easily applied in a simple manner to the rubber, leather or composition outer sole of a shoe for use either in converting ordinary shoes or in the manufacture of new shoes for golf and the like.

25 Another specific object of this invention is to provide an improved detachable calk which may be readily firmly applied to or detached from its sole receiving and supporting member by a novice with the aid of any ordinary wrench or pliers.

30 A further specific object of my present invention is to provide an improved calk assemblage wherein the anchoring means for the calk is adapted to be firmly and non-rotatably secured to the shoe sole in a simple and improved manner.

35 Still another specific object of the present invention is to provide an improved calk assemblage wherein an extensive bearing surface is provided along the outer or lower surface of the shoe sole to prevent inward displacement of the calk assemblage and to maintain the calk at a right angle relative to the sole.

40 An additional specific object of the present invention is to provide an improved calk assemblage which may be manufactured, sold and applied at moderate cost, and wherein the calk and its receiving or mounting unit is constantly resiliently urged outwardly of the lower surface of the sole to cushion and absorb shocks and to maintain constant compression stress on the mounting nut or bushing to prevent loosening thereof.

45 These and other specific objects and advan-

tages of the present invention will be apparent from the following detailed description.

A clear conception of the several features constituting my present improvement, and of the mode of constructing and of utilizing calk assemblages embodying the invention, may be had by referring to the drawing accompanying and forming a part of this specification, wherein like reference characters designate the same or similar parts in the various views.

Fig. 1 is a fragmentary outside view of the sole of a golf shoe provided with one of my improved calks and the mounting therefor;

Fig. 2 is a central vertical section through the sole fragment and the improved calk assemblage;

Fig. 3 is a fragmentary inside view of the sole and calk assemblage;

Fig. 4 is a plan view of the bearing member or disk of the improved calk assemblage;

Fig. 5 is a part sectional side view of the calk nut or receiving and mounting bushing of the assemblage; and

Fig. 6 is a transverse section through the nut or bushing taken along the line 6-6 of Fig. 5.

While the invention has been shown and described herein as being particularly embodied in and advantageously applied to a golf shoe calk assemblage, it is not desired or intended to thus unnecessarily restrict or limit the scope or utility of the improved features by virtue of such limited embodiment.

Referring to the drawing, wherein the reference numeral 10 designates the outer rubber or composition sole of a golf shoe or the like having inner and outer surfaces 11, 12 respectively and perforations 13 therein, the improved calk assemblage comprises, in general, a calk nut or receiving and mounting bushing 14 snugly confined within each perforation 13 and having internal threads 15 to form a socket member; a relatively thin plate 16 of spring metal or the like coacting with one end of the nut or socket member 14 and extending laterally therefrom adjacent the outer surface 12 of the sole 10 to provide a bearing means; and a calk 17 having a base flange 18 and a conical spike 19 formed integral therewith and extending away from one side thereof and an integral projection or shank 20 provided with external threads 21 extending away from the opposite side thereof and adapted for coaction with the internal threads 15 of the socket member 14.

To prevent rotation of the nut or socket member 14 upon application or removal of the calk 17, the member 14 is formed with a square or otherwise polygonal transverse cross-section intermediate its ends as at 22, that being the portion which is snugly confined within the perforation 13 of the sole 10; and the opposite end portions of the member 14 are provided of reduced dimensions as indicated at 23, 24, thus being adapted to be riveted over the adjacent inner and outer sole surfaces 11, 12 respectively.

The resilient plate 16 is formed with a central aperture 25 adapted for reception on the reduced outer end portion 24 of the nut so as to be firmly secured thereto upon riveting of this end portion 24; and the plate 16 is additionally dished as shown in Fig. 2 so as to peripherally engage the sole 10 and maintain the nut or member 14 under constant compression stress and constantly resiliently urge this member 14 outwardly of the sole bottom 12. The plate 16 is also preferably provided with an annular series of peripheral lobes 26 as clearly shown in Figs. 1 and 4 so that direc-

tional strains, particularly during walking, are absorbed by the resilient plate 16, which obviously provides a flexible support for the member 14.

The calk 17 may be attached to or detached from the socket member 14 in an obvious manner through coaction of the screw threads 15, 21 of the member 14 and calk shank 20 respectively; and the base flange 18 of the calk is recessed as at 27 adjacent the threaded projection 20 so as to clear the riveted end 24 of the socket member 14 and peripherally contact the plate 16 as shown in Fig. 2. This calk base flange 18 is furthermore hexagonal or otherwise polygonally shaped to enable ready application and/or removal with the aid of a standard wrench or pliers.

The improved anchoring means may obviously be readily applied to the outer shoe sole 10 by first providing the desired number of perforations 13 therein, thereafter inserting one of the socket members or nuts 14 within each perforation 13 with the polygonal portion 22 thereof being snugly confined within the perforation and the reduced portions 23, 24 projecting from opposite sides of the sole 10, then placing the dished plate 16 in position on the outer reduced portion 24 with the periphery thereof engaging the outer surface 12 of the sole, and finally riveting the reduced ends 23, 24 of the member 14 so as to form laterally extending retaining flanges. The threaded shank 20 of the calk 17 may then be screwed into the threaded socket member 14 with the aid of any standard wrench or pliers and the assemblage is complete.

From the foregoing detailed description of a typical embodiment of my invention, it is apparent that I have provided an improved calk assemblage which is simple in construction, flexible in its adaptations, and highly efficient in actual use. The internally threaded socket member 14 is firmly secured to the outer sole 10 of a shoe by riveting the thin end portions 23, 24 and is prevented from inward displacement during walking by the outer dished resilient plate 16 which forms a rather extensive bearing surface remote from the socket. The plate 16 may be made of spring steel and is preferably formed with peripheral lobes 26 which absorb directional strains during walking, and this plate 16 likewise prevents tilting and loosening of the member 14 and calk 17 upon application of pressure. The improved assemblages may be satisfactorily utilized with rubber or composition as well as leather soles, and they may obviously be likewise used either in the manufacture of new shoes or in converting ordinary shoes to cleated shoes. The polygonal cross-section of the intermediate portion of the member 14 prevents turning of this member during application and removal of the calk 17, and the polygonal shape of the base flange 18 permits use of an ordinary wrench or pliers during such application or removal operation. The invention has been shown and described as being embodied in a golf shoe, but it is not necessarily confined thereto and may be adapted to other types of shoes.

It should be understood that it is not desired to limit this invention to the exact details of construction or to the precise mode of use, herein shown and described, for various modifications within the scope of the claims may occur to persons skilled in the art to which this invention pertains.

I claim:

1. A calk assemblage for a perforated shoe sole comprising, an internally threaded socket

member snugly confined within the perforation of the sole, said socket member being formed with a polygonal transverse cross-section intermediate its ends to prevent rotation thereof and having opposite end portions of reduced dimensions adapted to be riveted over the adjacent inner and outer sole portions, a resilient plate embracing one of said reduced socket member portions beneath the riveting thereof and extending laterally therefrom against the outer surface of said sole to form an extensive bearing surface, and a calk having a base flange and a conical spike formed integral therewith and extending away from one side thereof and an integral externally threaded projection extending away from the opposite side thereof and adapted for coaction with said internally threaded socket member.

2. A calk assemblage for a perforated shoe sole comprising, an internally threaded socket member snugly confined within the perforation of the sole, said socket member being formed with a polygonal transverse cross-section intermediate its ends to prevent rotation thereof and having opposite end portions of reduced dimensions adapted to be riveted over the adjacent inner and outer sole portions, a resilient plate embracing the outer socket member portion within the riveting thereof and extending laterally therefrom against the outer surface of said sole to form an extensive bearing surface, and a calk having a base flange and a conical spike formed integral therewith and extending away from one side thereof and an integral externally threaded projection extending away from the opposite side thereof and adapted for coaction with said internally threaded socket member, said base flange being recessed adjacent the threaded projection thereof to clear the riveted end of said socket member and peripherally contact said bearing plate.

3. A calk assemblage for a perforated shoe sole comprising, a socket member snugly non-rotatably confined within the perforation of the sole, a resilient plate coacting with one end of said socket member and extending laterally therefrom adjacent the outer surface of said sole, said plate being dished so as to peripherally engage

said sole only remote from the said socket member and provide a flexible support for the socket, and a calk having a base flange and a conical spike formed integral therewith and extending away from one side thereof and an integral projection extending away from the opposite side thereof and adapted for coaction with said socket member, the base flange of said calk being formed for direct seating engagement with the outer surface of said resilient plate.

4. A calk assemblage for a perforated shoe sole comprising, an internally threaded socket member snugly non-rotatably confined within the perforation of the sole, a resilient plate secured to one end of said socket member by riveting and extending laterally therefrom adjacent the outer surface of said sole, said plate being dished so as to peripherally engage said sole only remote from said socket member and to provide a flexible support for the threaded socket, and a calk having a base flange and a conical spike formed integral therewith and extending away from one side thereof and an integral externally threaded projection extending away from the opposite side thereof and adapted for coaction with said internally threaded socket member, the base flange of said calk being recessed adjacent the threaded projection thereof to clear the riveted end of said socket member and peripherally contact said resilient plate.
